UNITED STATES PATENT OFFICE.

FRED TERSTEGEN, OF ELIZABETH, NEW JERSEY.

REPEATING ATTACHMENT FOR WATCHES.

SPECIFICATION forming part of Letters Patent No. 436,162, dated September 9, 1890.

Application filed April 16, 1890. Serial No. 348,148. (No model.)

To all whom it may concern:

Be it known that I, FRED TERSTEGEN, of Elizabeth, in the county of Union and State of New Jersey, have invented a new and useful Improvement in Repeating Attachments for Watches and other Time-Pieces, of which the following is a specification.

This invention constitutes a further development of the repeating mechanism for watches and other time-pieces, for which Letters Patent of the United States No. 311,270 were granted to me January 27, 1885.

My present invention relates, first, to the connection of the time mechanism with the repeating mechanism; second, to the application of repeating mechanism to stop-watches and the connection of the time-train of such watches with the repeating mechanism; third, it relates to the gearing which regulates the striking of the time.

The object of the first part of this invention is to connect the repeating mechanism, when placed on the plate of the watch-movement, with the time-train in both full and three-quarter plate watches; and this part of the invention, so far as it relates to full-plate watches, consists in connecting the snail of the repeating mechanism by means of a train of gearing carried from the back plate of the movement through to the front plate and the cannon-pinion or dial-wheels; as it relates to three-quarter plate watches, the invention consists in gearing the snails, when placed on the back of the movement, directly with the center-post, which carries the minute-hand.

The object of the second part of my invention is to connect the repeating mechanism with the time-train of complicated watches known as "stop-watches;" and this consists in connecting the snail or snails of the repeating mechanism, when placed on the back of the movement, by a train of gearing with the cannon-pinion or dial-wheels on the front plate of the movement.

A further object of the invention is to apply a repeating attachment or mechanism to the back of stop-watches. This consists in a stop-watch having repeating mechanism placed on its back plate and receiving its motion from the cannon-pinion by a train of gearing carried through the watch-movement.

A further object of the invention is to fa-

cilitate the setting of the repeating mechanism. This consists in arranging the setting mechanism to disconnect from the regulating-wheels when setting the repeating mechanism and connect with the same when the setting is completed and the striking mechanism commences to strike the time.

In the accompanying drawings, Sheet I, Figure 1 represents a repeating attachment applied directly to the back of a watch-movement without the intervention of a repeater-plate. Fig. 1^a is a plan of the under side of the cap or bridge on which the regulating-wheels are placed, also showing part of the train of gearing that connects the snails with the cannon-pinion on the front plate, which is placed on the back plate. Fig. 1^b is an edge view of the same, showing also the regulating-wheels. Fig. 2 represents a sectional edge elevation of a watch-movement without the time-train and showing the gearing-connection of the repeating mechanism with the cannon-pinion. Fig. 2^a shows that part of the snail-connecting gearing which is placed on the front plate. Fig. 3 represents the repeating mechanism applied to a three-quarter-plate watch (without stop-watch attachments) and the connection of the snail with the center-post at the back of the movement. Figs. 3^a and 3^b represent, respectively, a side elevation and a plan of the gearing on a three-quarter-plate watch connecting the snail with the time-train. Fig. 4 represents the under side of a repeater-plate, showing the manner of connecting the gearing with the snail in full-plate watches. Fig. 5 represents a repeating attachment in which the hours and its divisions are struck by separate racks applied to a three-quarter-plate watch, also illustrating the connection with the time-train. Sheet II: Fig. 5^a represents, on an enlarged scale, the setting and winding mechanism, showing a shifting-wheel disconnected from the regulating-gearing when setting the repeater; Fig. 5^b, the same when the repeater is set and the shifting-wheel in connection with the regulating-gearing; Fig. 5^c, the upper side of the repeater-plate; Fig. 5^d, details of the gearing. Sheet III: Fig. 6 represents the repeating mechanism applied to a stop-watch. Fig. 6^a shows the front plate of the same and the gearing which connects the snail of the repeating mechanism with the

time-train. Fig. 6^b is a side elevation of the stop-watch, showing the connection of the gearing through the movement from the back to the front plate of the repeating mechanism 5 with the time-train. Fig. 6^c represents the repeater plate and bridge of the repeating mechanism detached from the stop-watch. Sheet IV: Fig. 7 represents the repeating mechanism or attachment applied to an open-faced stop-watch. Fig. 7^a represents the front plate of the same and the gearing which connects the snail of the repeating mechanism with the time-train. Fig. 7^b represents the under side of the front plate, showing the 15 manner of fastening the gearing to the plate. Fig. 8 represents a split-seconds stop-watch with the repeater-plate removed. Fig. 8^a represents the repeater-plate for split-seconds watches with the repeating mechanism attached thereto. Fig. 8^b represents the under bridge of the repeater-plate. Fig. 8^c represents the upper bridge or repeater-plate. Fig. 8^d represents one edge view of the repeater-plate or bridges.

25 Referring to the drawings, A represents the watch-movement, B the repeater-plate, and C the plate or bridge under which are placed the regulating-wheels of the repeating mechanism.

30 In Fig. 1 the repeating mechanism is placed directly on the back plate of the watch, the lever, hammers, clicks, bell-wires, springs, &c., being attached directly to the surface of the said plate. In this arrangement a two 35 part cap or bridge C C' is used for the staffs of the regulating-wheels, gearing, and snails. The train of gearing for a full-plate watch is arranged as follows: From the cannon-pinion 1 on the front of the watch (see Figs. 2 and 40 2^a) a train of wheels communicates the motion of the said pinion to a pinion 2 on one end of a staff v that is passed through the watch-plates from front to back, and on its opposite end carries a pinion 3 above the back plate. This pinion meshes with a large wheel 4, Figs. 1, 1^a, and 1^b, in recess in the under side of bridge C'. Wheel 4 in turn meshes with the pinion 5 on the snail-shaft, as represented clearly in Figs. 1^a and 1^b. The gearing on the 45 front plate is illustrated in Figs. 2 and 2^a. In this way, as will be readily seen, the motion of the minute-hand is communicated to the snail, which moves the star-wheel 6 carrying the hour-snail 7.

50 The mode of connecting the repeating mechanism with the time-train, just described, for full-plate watches is also applied to stop-watches. (See Figs. 6, 6^a, and 6^b, Sheet III.)

55 Figs. 3, 3^a, and 3^b, Sheet I, illustrate the application of the repeating mechanism to a three-quarter-plate watch and its connection with the time-train. In the representation of the back of a watch, Fig. 3, a repeater-plate B is used to carry the repeating mechanism; but 60 it can be applied directly to the watch-plate, if desired. The connection between the time-train and the repeating mechanism is made

by means of two wheels xx' . The first is placed on the center-post P, (which may have its ends above the wheels squared in key-winders,) 70 that moves with the minute-hand. The other wheel x' is placed on the staff of the snail that moves the star-wheel, as shown in Figs. 3^a and 3^b. In this way the repeating mechanism on the back of the watch is geared directly 75 to the center-post and thence to the time-train.

Fig. 4 represents the under side of the repeater-plate, which carries the repeating mechanism, showing also that part of the gearing 80 for full-plate watches which lies on the back plate when a repeater-plate is used. In this case the wheel 4 and pinions 3 and 5 are pivoted to the under side of the repeater-plate B instead of to a bridge C', as in Fig. 1. The 85 star-wheel 6 and snail 7 (see Fig. 3) are placed on the upper side of the plate—the star-wheel in a recess 8, so that it is in position to be controlled by the escapement-spring u that is attached to the under side of the plate in a 90 suitable recess, as shown in Fig. 4. In this figure are also illustrated the screw-holes and pivot or staff holes for the several parts of the repeating mechanism.

Fig. 5 shows a repeating mechanism in 95 which the hour and its divisions are struck by separate racks applied to a three-quarter plate watch-movement. This mechanism and the manner of connecting it with a plate and applying it to the back of a watch-movement 100 are fully described in my patent, No 421,844, dated February 18, 1890, filed April 23, 1884. There are two snails 7 7'. The former is the hour-snail and the latter a five-minute snail; but I do not limit the invention to this mode 105 of dividing the time. The snail 7' is geared directly to the center-post P, as in Fig. 3, by the wheels xx' , the former on the center-post and the latter on the snail-staff.

Figs. 5^a to 5^d, Sheet II, show the setting and 110 gearing mechanism of the repeating mechanism in connection with the regulating-wheels that control the speed of the striking mechanism. The lever L and winding-segment M are connected in the usual manner, which 115 is fully described in my patent above referred to; but the ratchet-wheel on the hour-striking disk e is dispensed with as a means of holding the barrel-wheel, and in its stead is substituted a shifting-wheel 10, which is connected by an arm 11 with the staff of the regulating-wheel 13, so as to move loosely thereon. This shifting-wheel is thrown out of connection with the pinion of the anchor or escape wheel 14 when the repeater is set 120 and the mainspring wound up, as shown in Fig. 5^a; but when the repeating mechanism commences to move back to strike the time the shifting-wheel is thrown in gear with the regulating-wheel 14, as shown in Fig. 5^b, and 125 thus the strokes of the hammers are separated or regulated by proper intervals.

Sheet III, Fig. 6: The repeating mechanism is applied to a stop-watch in this example.

For this purpose the bridge D is cut off just beyond the center-post on one side, and an extension D', projecting away from the center-post at a sharp angle, is added to the bridge, and is provided beyond the periphery of the center-seconds or stop-wheel 15 with screw-holes, through which are passed the screws which fasten the end of the bridge to the watch-plate. The object of shortening the bridge D is to obtain space for the repeater-plate B, Figs. 6 and 6^c, between the center-post and the periphery of the watch. The repeater-plates are composed of upper bridge C and lower bridge B. The latter extends from the starting-spring 16 of the stop mechanism at dotted line B² to the end of the projection B', and the upper bridge C extends beyond the lower bridge and over the starting-spring of the stop-watch mechanism and terminates at B³. Between the end of the repeater-plate and the bridge D a space A' is left on the watch-plate for the split-seconds attachment. The connection of the repeating mechanism with the time-train in the stop mechanism is made with the cannon-pinion on the front of the watch in the same manner as described heretofore in connection with Figs. 1, 2, and 2^a, and the wheel or pinion 3 gears directly on wheel or pinion 5 on the snail-shaft. (Shown in Fig. 6^c.)

Fig. 6^a shows the gearing and connection with the cannon-pinion on the front of the watch. Fig. 6^b shows the shaft passed through the movement-plates with the pinions 2 and 3 attached thereto to connect the front and back gearing together; and Fig. 6^c shows an edge view of the upper bridge C and the lower bridge B used in stop-watches for the attachment of the repeating mechanism, and shows the wheel or pinion 5 attached to the snail 7', which moves the star-wheel 6 of hour-snail 7.

Sheet IV: Figs. 7 to 7^b illustrate the application of the repeating mechanism or attachment to open-face stop-watches, and Fig. 8 the same with a split-seconds attachment. In this application the bridge is not shortened; but a recess D² is turned in the bridge D at one end for the snail of the repeater and another recess D³ in the opposite end for the hammer. The repeating mechanism is connected by suitable gearing through the watch-plates with the cannon-pinion on the front of the watch; but the gearing or connecting wheels in the front plate are arranged differently from those previously described. In Fig. 7^a is shown a series of wheels leading from the cannon-pinion 1 and set in recesses in the under side of the front plate, where they are held by a cap-plate F. (See Fig. 7^b, which shows the plate, Fig. 7^a, inverted.) The said wheels communicate motion to the pinion 2 and thence to the repeating mechanism, as before described. In Figs. 7 and 8, A' represents the space on the back plate of the watch for the split-seconds attachment 17, which is shown applied to the said space in Fig. 8.

Fig. 8^a represents the repeating attachment

detached from the watch as used with the stop-watch and split-seconds movements, Figs. 7 and 8.

Fig. 8^b represents the lower plate B of the repeating attachment with the hammers and bell-wires attached, showing also the projection B', to which the bell-wires are fastened.

Fig. 8^c represents the upper bridge C detached from the repeater-plate B, with the hour-piece H indicated by dotted lines. This hour-piece is placed in a slot made in the under side of the bridge C, where it is held in place by the end I of the escapement-spring u, which lies across it, as shown by the dotted lines. The hour-piece is moved and the rack which strikes the division of the hour is released in the same manner as described in my patent above referred to.

Fig. 8^d is an edge view of the plate B and the bridge C, being placed together, and with the several parts of the repeating mechanism which are held between them exposed.

I do not limit myself to the exact means of making the connection between the repeating mechanism and the time-train in watches herein described and shown, as it is obvious that the same may be varied without departing from the principle of my invention.

I claim—

1. In repeating mechanism for watches, the combination, with the cannon-pinion 1 and the pinion 5 on the snail for the divisions of the hour, of a series of wheels connecting pinions 1 and 5 with each other through the plates of the movement, substantially as specified.

2. A watch-movement having a stop-watch mechanism arranged on its back plate, in combination with a repeating mechanism which is arranged on the back of the watch-movement and has its snail that receives motion from the time mechanism connected with said time mechanism by suitable gearing connecting the said snail with the dial-wheels, substantially as specified.

3. In combination with a stop-watch mechanism arranged on the back plate of a watch-movement, a back plate of a watch-movement and a repeating mechanism attached to and arranged on the back plate of a watch-movement, substantially as specified.

4. The combination, in a watch-movement of a back plate, a stop-watch mechanism and a split-seconds mechanism arranged on the said back plate, and a repeating mechanism arranged on the said back plate and having its snail that receives motion from the time mechanism connected with said mechanism by suitable gearing connecting the said snail with the dial-wheels, substantially as specified.

5. The combination of the setting device of a repeating mechanism for watches and a shifting-wheel which disconnects the setting mechanism from the regulating-wheels when the repeating mechanism is set and connects the same with the regulating-wheels when

the repeating mechanism commences to operate to strike the time, substantially as specified.

6. The combination of a setting-lever for 5 retracting the motor-spring of a repeater mechanism, a motor-spring and a shifting-wheel which disconnects the setting and actuating mechanism from the regulating-wheels when the repeating mechanism is set and 10 connects the same with the regulating-wheels

when the repeating mechanism commences to operate to strike the time, substantially as specified.

In testimony that I claim the foregoing as my invention I have hereunto subscribed my 15 name the 15th day of April, 1890.

FRED TERSTEGEN.

In presence of—

WILTON C. DONN,
ANTON T. HABERMEHL.
